[57] CLAIM

The ornamental design for a paper product, as shown and
described.

DESCRIPTION

FIG. 1 is a top front perspective view of a paper product,
showing our new ornamental design.

FIG. 2 is a rear elevational view of the paper product shown
in FIGS. 1.

FIG. 3 is a top plan view of the paper product shown in
FIGS. 1 and 2, the opposite (bottom) side view being a
mirror image thereof.

FIG. 4 is a side elevational view of the paper product shown
in FIGS. 1, 2 and 3, the opposite side elevational view being
a mirror image thereof; and,

FIG. 5 is a frontal elevational view of the paper product
shown in FIGS. 1, 2, 3, and 4, the frontal elevational view
being the opposite view of the rear elevational view shown
in FIG. 2.

It is to be understood that the design pattern shown in FIGS.
1–5 continues throughout the length and width of the paper
product; the paper product is shown broken away to indicate
that the paper product has indeterminate length and width.
The broken lines are for illustrative purposes only and form
no part of the claimed design.
